UNITED STATES PATENT OFFICE.

HAROLD G. WARR, OF CHICAGO, ILLINOIS, ASSIGNOR TO THE P. & M. COMPANY, OF CHICAGO, ILLINOIS, A CORPORATION OF ILLINOIS.

RAIL-ANCHOR.

1,217,541.

Specification of Letters Patent. Patented Feb. 27, 1917.

Application filed August 24, 1914. Serial No. 858,230.

To all whom it may concern:

Be it known that I, HAROLD G. WARR, a citizen of the United States, residing at Chicago, in the county of Cook and State of Illinois, have invented certain new and useful Improvements in Rail-Anchors, of which the following is a specification.

My invention relates to a device for preventing the longitudinal creep of railroad rails, these devices being commonly called rail anchors, rail stays or anti-creepers, and particularly to a device in which one or preferably both of the elements constituting the rail clamp are resilient and are strained by the application of the device to the rail, so as to resist a retrograde movement as between the elements, tending to loosen the grip of the device on the rail and hence diminish its holding power. A rail anchor is subjected not only to the forward stress caused by the creeping tendency of the rail, but also to vibration and to certain forces which operate at times in the direction contrary to the forward creep of the rail, tending to move the device away from the tie against which it is abutting and to loosen the grip of the parts between themselves and upon the rail. Unequal expansion and contraction of the rail and parts of the anchor, due to temperature changes, also tend to destroy, unless checked, the holding power of the device.

The primary object of my invention is to provide a rail anchor comprising a plurality of co-engaging elements which together grip the rail, for example, the base flange thereof, and are so constructed and arranged that the forward creep of the rail produces a positive wedging action between the elements, whereby said tendency to creep is self checked, one or both of the elements being resilient and strained by application of the device to the rail so that vibration and shrinkage of metal due to temperature changes is absorbed and any tendency which the parts of the device may have toward a loosening or retrograde relative movement is prevented.

A further object of the invention is to provide a rail anchor which will be inexpensive to manufacture, strong and durable and, at the same time, light in weight. Weight is

an important consideration as well in the cost of transportation as in cost of manufacture.

The invention is illustrated in certain preferred embodiments in the accompanying drawings, wherein—

Figure 1 is a sectional elevation, of a rail anchor constructed in accordance with the invention shown as applied to a rail, the view looking toward the tie against which the device is abutted.

Fig. 2 is a side elevation of the tie abutting element of the device, shown in the position which it assumes before the other element, the yoke, is put in place;

Fig. 3, a longitudinal section taken through the device and the rail and tie, illustrating the relation of the parts in their operative positions;

Figs. 4 and 5, views, in perspective, of the tie abutting element and yoke element respectively;

Fig. 6, an elevation illustrating particularly the method of applying the device to the rail;

Figs. 7 and 8, similar views illustrating a modified form of yoke;

Fig. 9, a view, in perspective, of the yoke shown in the preceding two figures;

Fig. 10, a longitudinal sectional view of a rail anchor constructed on the same principles as the anchors shown in Figs. 1 to 9 but modified in respect to the form of the tie abutting member; and

Fig. 11, a view, in perspective, of the tie abutting element in this form of the invention.

Like characters of reference designate like parts in the several figures of the drawings.

Referring to the drawings, A designates a railroad rail and B one of the cross ties on which the rail is supported.

The rail anchor illustrated in Figs. 1 to 6 inclusive, consists of two co-engaging elements, a tie abutting element C and a yoke D. The tie abutting element C is in the form of a plate adapted to bear against the cross tie B and provided with a tongue E preferably formed at its outer end with an upward bend F. This element is preferably made of sheet metal, sheet steel, for ex-

ample; and the tongue is formed with a tapered depression G constituting in effect a wedge.

The yoke element D is adapted to extend around the base of the rail and the tongue E lying under said rail base. The yoke is preferably formed at the middle with a bend or indentation H and at one end with grooves I for the application of a claw bar.

In applying the device to a rail, the tie abutting member C is placed under the rail base against the tie, as shown in Fig. 2. The yoke is slipped under the rail and around the tongue E so that it assumes the position shown in Fig. 6. The recessed end of the yoke is then engaged by a claw bar J, and is raised and at the same time forced toward the rail into the position shown in Figs. 1 and 3. This bends the part of the tongue beyond or backward of the wedge G, as best shown in Fig. 3. The yoke may then be driven up the wedge G toward the tie as far as may be necessary to obtain a secure hold on the rail. With the parts of the device in this position a wedge G opposes the further movement of the yoke toward the tie, against which, it will be understood, the other element bears. A forward creep of the rail, which is imparted to the yoke D, produces a positive wedging action between the elements of the anchor that increases the grip of the device on the rail so that the creeping movement is self checked. On the other hand, any retrograde movement of the yoke D is checked by the downward slope of the outer end of the tongue E resulting from the bending of the tongue. The elastic relation between the two elements absorbs vibration and slight shrinkages of metal due to temperature changes. In order to facilitate the application of the yoke, the end provided with the claw bar recess I may be formed with a cam surface K which rides over the edge of the rail base. As a matter of fact, it would be possible to apply the device without the use of a claw bar, in which case the recess I might be omitted.

In Figs. 7 to 9 inclusive, I have shown an anchor consisting preferably, though not necessarily, of two parts constructed like those of the anchor just described except that the yoke member is modified so that one of its jaws will take a cramping or biting hold on the rail and the other a wedging grip when the device is in operative position. When so constructed the yoke will move forwardly with the rail when the latter creeps. It is functionally part of the rail. Fig. 7 shows the position of the yoke when first applied to the rail. Fig. 8 shows the elements of the anchor in their operative position. The yoke designated D' is formed at one end with a bend d so that when the yoke is adjusted to its position on the rail base the jaw

on this end takes the desired cramping grip on the edge of the rail base. The other end may be formed with a bearing d' for the under surface of the opposite edge of the rail base. As the surface d' of the yoke has the slope of the upper face of the rail base the transverse movement of the yoke in adjusting it to its final position gives it a wedging grip on the edge of the rail base at this side.

In Figs. 10 and 11 I have shown a rail anchor constructed upon the same principles but in which the tie abutting member is structurally different. The yoke member here designated D'' may be substantially the same as the yoke member D heretofore described. The tie abutting member L is made of rolled tapered stock so that the tongue M is thickest near the tie abutting plate and thins down toward its extremities. When the device is applied to the rail, the thin flexible end of the tongue is bent and the same result obtained as in the other form of the invention; that is, the forward movement of the yoke is checked by a positive wedging action between the yoke and the tongue M while the movement of the yoke away from the tie is checked by the bent end of the tongue.

While I have shown and described the invention in certain preferred embodiments, further modifications might be made without departure from the principles of the invention. Therefore I do not wish to be understood as limiting the invention to the particular constructions, arrangements and devices shown and described except so far as the same are specifically made limitations in certain of the claims herein.

I claim:

1. A rail anchor comprising two co-engaging rail clamping elements, one of which is adapted to bear against a tie and the other to be free therefrom; said elements being constructed so that they have a positive wedging action one upon the other when the free member moves toward the tie, one of said elements being resilient and strained by application of the device to the rail so that a retrograde movement of the free member is checked.

2. A rail anchor comprising two co-engaging rail clamping elements, one of which is adapted to bear against a tie and the other to be free therefrom; said elements being constructed so that they have a positive wedging action one upon the other when the free member moves toward the tie, the element bearing against the tie being resilient and strained by application of the device to the rail so that it checks the tendency of the free member to move away from the tie.

3. A rail anchor comprising two co-engaging rail clamping elements, one of which

is adapted to bear against a tie and the other to be free therefrom; said elements being constructed so that they have a positive wedging action one upon the other with a 5 relative movement of one element with respect to the other in one direction, one of said elements being resilient and strained by application of the device to the rail so as to check a relative movement of said one element with respect to said other element in the other direction.

4. A rail anchor comprising a rail embracing element extending around the base of the rail, and a resilient member having a 15 wedge-shaped portion tapering in thickness lengthwise of the rail which, when said member is unbent, stands away from the rail, but is adapted to be bent by the rail embracing element into contact with the rail 20 to provide a substantially rigid wedge with which said rail embracing element engages.

5. A rail anchor comprising a rail embracing element extending around the base of the rail, and a resilient member having a 25 tie abutting plate and a wedge-shaped portion tapering in thickness lengthwise of the rail which, when said member is unbent, stands away from the rail, but is adapted to be bent by the rail embracing element into 30 contact with the rail to provide a substantially rigid wedge with which said rail embracing element engages.

6. A rail anchor comprising a rail embracing element extending around the base 35 of the rail and a resilient member having a wedge-shaped portion tapering in thickness lengthwise of the rail, which lies under the base of the rail and, when said member is unbent, stands away from the same 40 but is adapted to be bent by the rail embracing member so that it will lie along in contact with said rail base to provide a substantially rigid wedge with which said rail embracing element engages.

45 7. A rail anchor comprising a rail embracing element extending around the base of the rail and a resilient member having a tie abutting plate, and a wedge-shaped portion tapering in thickness lengthwise of the rail, which lies under the base of the rail and, when said member is unbent, stands away from the same but is adapted to be bent by the rail embracing member so that it will lie along in contact with said rail 50 base to provide a substantially rigid wedge with which said rail embracing element engages.

8. A rail anchor comprising a rail embracing element extending around the base 55 of the rail, and a resilient tongue adapted to bear against the rail at opposite ends, a portion of said tongue being tapered in thickness lengthwise of the rail and adapted, when the tongue is unbent, to stand away 60 from the rail but to be bent into contact

therewith by said rail embracing element to provide a substantially rigid wedge with which said rail embracing element engages.

9. A rail anchor comprising a yoke member adapted to extend around the base of a 70 rail and a tongue adapted to be embraced by said yoke and pressed against the rail; the tongue being substantially rigid and formed with a wedge at one end and being resilient at the other end so as to be bent by said yoke; one of said members being provided with a tie abutting flange.

10. A rail anchor comprising a yoke member adapted to extend around the base of a rail and a tongue adapted to be embraced by 80 said yoke and pressed against the rail; the tongue being substantially rigid and formed with a wedge at one end and being resilient at the other end so as to be bent by said yoke; said tongue being provided with a tie 85 abutting flange.

11. A rail anchor comprising a yoke adapted to extend around the base of a rail and a tongue embraced by the yoke so as to be pressed against the rail and formed with 90 a tie abutting flange; said tongue being substantially rigid at the end adjacent the tie abutting flange and formed at that end with a wedge which is deepest at said flange, and being resilient at the other end. 95

12. A rail anchor comprising a yoke and a sheet metal element bent so as to form a tie abutting flange and a tongue adapted to be embraced by said yoke; said tongue being formed so as to bear on the rail at opposite 100 ends and to stand out of contact with the rail at intermediate points and having a tapered depression which is deepest at said tie abutting flange.

13. A rail anchor comprising a rail embracing element extending around the base of the rail, and a resilient tongue adapted to lie under the base of the rail in contact therewith at opposite ends and having a tie 105 abutting plate, a portion of said tongue being tapered in thickness lengthwise of the rail and adapted, when the tongue is unbent, to stand away from the rail but to be bent into contact therewith by said rail embracing element to provide a substantially rigid 110 wedge with which the rail embracing element engages.

14. A rail anchor comprising a member a portion of which is wedge-shaped and adapted to lie along and in contact with the under 115 surface of the base flange of a rail and a portion of which is flexible and adapted to bear against the rail only at its extremity, said member being provided with a tie abutting flange, and a yoke extending around said 120 base flange and member so as to subject the latter to a bending strain.

15. A rail anchor comprising a member, a portion of which is wedge-shaped and adapted to lie along and in contact with the rail 125

and a portion of which is flexible and adapted to bear against the rail only at its extremity, said member being provided with a tie abutting flange, and a yoke adapted to extend around the base flange of the rail and said member so as to subject the latter to a bending strain.

16. A rail anchor comprising a member, a portion of which is wedge-shaped and adapted to lie along and in contact with the rail, a portion of which is flexible and adapted to bear against the rail only at its extremity and a yoke adapted to extend around the base flange of the rail and said member so as to subject the latter to a bending strain.

17. A rail anchor comprising a member a

portion of which is wedge-shaped and adapted to lie along and in contact with the under surface of the base flange of a rail and a portion of which is flexible and adapted to bear 20 against the rail only at its extremity, said member being provided with a tie abutting flange, said member being deepest at the end adjacent said flange and tapering toward the other end, and a yoke extending around said 25 base flange and member so as to subject the latter to a bending strain.

HAROLD G. WARR.

Witnesses:

L. A. FALKENBERG,
G. Y. SKINNER.

It is hereby certified that in Letters Patent No. 1,217,541, granted February 27, 1917, upon the application of Harold G. Warr, of Chicago, Illinois, for an improvement in "Rail-Anchors," an error appears in the printed specification requiring correction as follows: Page 2, after line 104, insert the paragraph:—

The form of the invention shown in Figs. 6 to 9, inclusive, is not specifically claimed in this application, as it forms the subject-matter of an application filed June 3, 1916, Serial No. 101,433.;

and that the said Letters Patent should be read with this correction therein that the same may conform to the record of the case in the Patent Office.

Signed and sealed this 31st day of July, A. D., 1917.
